UNITED STATES PATENT OFFICE

2,542,342

FOLDING CHAIR

Charles E. Meeker, Detroit, Mich.

Application December 3, 1945, Serial No. 632,357

3 Claims. (Cl. 155—198)

1

This invention relates to chairs and in particular to foldable chairs.

One object of this invention is to provide a combination reclining chair and rocker which is collapsible into a small bundle for storage or transportation.

Another object is to provide a combination reclining chair and rocker having arm rests which are adjustable for height, thereby adding to the comfort of the occupant.

Another object is to provide a combination reclining chair and rocker having a flexible seat and back formed of textile material or the like with improved means for adjusting the length thereof and thereby adapting the chair quickly and easily to the comfort of the individual occupant or to occupants of different heights.

Another object is to provide a combination reclining chair and rocker having an attachable and collapsible leg rest which is also foldable in the same small bundle occupied by the rocker itself.

Other objects and advantages of the invention will become apparent during the course of the following description of the accompanying drawings, wherein:

Figure 1 is a side elevation of the combined reclining chair and rocker according to a preferred embodiment of the present invention, with the leg rest attached thereto;

Figure 2 is a top plan view of the chair shown in Figure 1;

Figure 3 is a vertical section through the leg rest, taken along the line 3—3 in Figure 1;

Figure 4 is a vertical section through the leg rest taken along the line 4—4 in Figure 1, showing one of the spreaders therefor;

Figure 5 is a perspective view of the spreader and its connections shown in Figure 4;

Figure 6 is a perspective view of a modification of the spreader shown in Figures 4 and 5;

Figure 7 is an enlarged fragmentary view of the upper right-hand corner of Figure 2, showing the means for adjusting the length of the chair back;

Figure 8 is a cross-section along the lines 8—8 in Figures 2 and 7;

Figure 9 is a perspective view of the upper end of the chair back and wedge stop shown in Figures 7 and 8;

Figure 10 is an enlarged perspective view of one end of a cross bar of the chair; and

Figure 11 is an enlarged perspective view of one end of an upright of the chair cooperating with and fitting into the cross bar end shown in Figure 10.

Referring to the drawings in detail, Figure 1 shows a preferred embodiment of the invention as consisting of a foldable chair unit, generally designated 10, to which is attached a foldable

leg rest unit, generally designated 11. The chair unit 10 consists of a pair of uprights 12 of elongated form and having angled lower ends 13 adapted to conform to the surface of the ground or floor when the uprights 12 are in their normal inclined position. The uprights 12 near their lower ends are provided with a spreader 14 pivotally secured thereto as at 15 and consisting of a pair of straps 16 and 17, preferably of metal and extending toward one another. The straps 16 and 17 are pivotally interconnected by a pivot fastener 18 (Figure 2) and a portion 19 of the strap 16 is bent perpendicularly to the upper edge thereof to engage the upper edge of the strap 17 at a short distance from the pivot pin 18. In this manner, the uprights 12 are permanently spaced apart by the spreader 14, but are also held together as a unit when the portions 16 and 17 of the spreader 14 are folded into positions lying alongside the uprights 12.

The upper ends of the uprights 12 are forked to provide a slot 20 (Figure 11) adjacent which are arms 21 with flared portions 22 at the ends thereof. The arms 21 are interconnected by a fastener 23 to prevent splitting and to further strengthen the ends of the uprights 12. The ends of the arms 21 are tapered on their opposite lateral faces 24 and 25 to render them wedge-shaped.

The uprights 12 are interconnected at their upper ends by a cross bar 26 (Figures 2 and 10), the ends of which are provided with downwardly diverging wedge-shaped grooves 27 and 28 on their opposite sides, these grooves corresponding to and mating with the tapered arms 21. The bridge portion 29 between the slots 27 and 28 is also of such width and thickness as to fit into the longitudinal slots 20 at the upper ends of the uprights 12. In this manner, the weight of a person in the chair 10 constantly urges the wedge-shaped arms 21 at the upper end of the uprights 12 into the corresponding wedge-shaped grooves 27 and 28, resulting in a tight connection therebetween which prevents wobbling, yet which is instantly separable when the chair is folded up.

The cross bar 26 is provided intermediate its ends with a slot 30 having sides 31 and 32 angled relatively to one another so as to provide a groove 50 of approximately triangular cross-section (Figures 7 and 8). Insertable in the wedge-shaped slot 30 is a wedging unit 33 of roughly triangular cross-section mating with the slot 30. The wedging unit 33 consists of a pair of elongated members 34 and 35 (Figure 9), each having a cross-section approximately that of a right triangle. The members 34 and 35 are clamped on opposite sides of the upper end of the chair back 36 and secured thereto by fasteners 37 with the bases of the members 34 and 35 upward. In assembly,

3

therefore, the members 34 and 35 form a unit of triangular cross-section which fits into the slot 30 and mates with the flared sides 31 and 32 thereof (Figure 8). This construction enables the chair back 36 to be adjusted for length to fit the desires of the particular individual occupant, the upper end of the chair back 36 being rolled up upon the unit 33 as a core. Since the chair back 36 is of flexible material, such as canvas or other textile material, the length thereof may be varied as desired, and the back 36 shortened or lengthened.

The opposite end of the chair back 36 is secured to a lower cross-bar 38 (Figure 2) by looping it around the cross-bar and securing the free end to the back 36 as by the transverse stitching 39. The ends of the cross bar 38 are grooved on their opposite sides as at 40 with wedge-shaped grooves similar to the grooves 27 in the ends of the upper cross bar 26 (Figure 10). Engaging and mating with the wedge-shaped grooves 40 are the wedge-shaped end arms 41 of the pair of standards 42. The end arms 41 are similar in configuration to the wedge-shaped end arms 21 on the upper ends of the uprights 12 (Figure 11) and have longitudinal slots 43 similarly engaging the bridge portion between the wedge-shaped grooves 40. This construction provides a firm yet instantly separable connection between the cross bar 38 and the standards 42, yet the weight of the occupant constantly urges these members together and prevents wobbling. The standards 42 are provided with fasteners 44 below the inner ends of the slots 43, thereby preventing splitting. The bottom ends 45 of the standards 42 are cut off at an angle in order to fit the ground, floor or deck where the chair is being used.

The lower ends of the uprights 12 and standards 42 are interconnected by flexible connectors 46, these being preferably chains with their opposite ends anchored to eye-bolts 47 secured respectively to the uprights 12 and standards 42. The ends 48 of the cross bar 38 are provided with fasteners 49 (Figures 1 and 2) serving as pivots and anchorages for the end links 50 of flexible connectors 51, preferably chains. The opposite portions of the flexible connectors 51 are adjustably secured to hooks 52 secured to the uprights 12, which are provided with recesses 53 beneath the ends of the hooks so as to facilitate the insertion of a link of the flexible connector 51. In this manner, the length of the flexible connectors 51 may be varied to vary the inclination of the standards 42 and uprights 12 relatively to each other and to the ground, floor or deck.

The uprights 12 are provided with adjustable arm rests 54 provided with slots 55 arranged obliquely thereto in a lengthwise direction so that the arm rests 54 are angled outward. The slots 55 form spaced arms 56 and 57 (Figure 2), these arms engaging the sides of the uprights 12. The outward angling of the arm rests 54 by reason of the obliquely-directed slots 55 prevents their interfering with or catching on the clothing of a person getting into or out of the chair, as well as insuring a more comfortable posture than if they were parallel. The arms 56 and 57 may be tightened against the uprights 12 by tightening the screws or bolts 58 which extend across the ends of the slots 55, behind the uprights 12. The forward edge or end 59 of the slot 55 is preferably V-shaped in vertical cross-section (Figure 1) with two relatively-angled faces in order to fit the inclined forward edge of the upright 12 more accurately. This makes the arm rests inter-

4

changeable for the right or left arm so that only one rest has to be made for use on both arms. Moreover, this construction also enables the arm rests to be interchanged so that both are inclined inward so as to be used by a child. The arm rests 54 are adjustable up or down along the uprights 12 as shown in chain lines in Figure 1, merely by lifting their outer ends and sliding them along the uprights 12. When the arm rest 54 is lowered at its adjusted position, the fastener 58 and groove end 59 cooperate to engage the forward and rearward edges 60 and 61 of the uprights 12. The weight of the user's arms upon the arm rests 54 increases the holding effect of the arm rests 54 at their adjusted positions.

The lower cross bar 38 is provided with apertures 62 adapted to receive the ends of bent hooks 63, these being mounted in the ends of the longitudinal frame members 64 of the leg rest 11 (Figures 1, 2 and 3). The ends are preferably surrounded by ferrules 65 in order to prevent splitting.

Pivots inserted in sockets 66 in the inner sides of the longitudinal frame members 64 are pivot pins 67 embedded in the upper ends of leg members 68 and 69 interconnected intermediate by the pivot fasteners 70 (Figure 3). The lower ends of the leg members 68 and 69 are angled as at 71 to fit the ground, floor or deck and are optionally provided with anti-slipping elements 72, such as rubber cups, domes or sockets, or spikes. It will be evident that spikes are especially useful when the device is made up in the form of camp chairs, as these spikes will enter the ground and firmly anchor the leg members 68 and 69 in position.

The longitudinal frame members 64 are interconnected by collapsible spreaders 73 composed of straps 74 and 75 (Figure 5) having slots 76 formed in their opposite ends to provide hinge pin portions 77, the latter being pivotally held by the U-shaped portion 78 of brackets 79 secured to the longitudinal frame members 64. The inner end of the strap 74 is similarly slotted as at 80 to provide a hinge pin portion 81 which is received within the U-shaped portion 82 of a bracket 83 secured to the strap 75. Located between the hinge pin portions 77 and 81 of the strap 74 are notches 84 (Figure 5) extending inwardly from the edges thereof and engaged by projections 85 formed in the free end of the strap 75 and bent at right angles thereto. The projections 85 are bent slightly toward one another to provide a detent action for releasably holding the straps 74 and 75 in engagement.

Extending between and secured at their opposite ends to the longitudinal frame members 64, as by the fasteners 86, are flexible cross members 87 and 88, preferably of textile material such as heavy canvas or web belting (Figures 2 and 4). Secured to the flexible cross members 87 and 88 are longitudinally extending slats 89 which provide leg rest portions for the leg rest unit 11. The slats 89 are secured to the flexible cross members 86 by any suitable means, such as by fasteners 90.

The modification shown in Figure 6 consists of a collapsible spreader 91 having a similar function to the collapsible spreader 73 shown in Figure 5, but consisting of straps 92 and 93 of channel cross-section having their ends cut away as at 94 to provide ears 95 engaging the upper and lower edges of the longitudinal frame members 64 and pivotally secured thereto by the pivot fasteners 96, extending through the cross members 64. The inner end of the strap 92 is cut

away as at 97 to provide ears 98 between which extends a pivot fastener 99, the intermediate portion of which passes through the tubular portion 100 of a bracket 101 secured to the web portion 102 of the strap 93. The side portions 103 of the strap 92 are bent slightly toward one another relatively to their web portion 104 so as to frictionally engage the side portions 105 of the strap 93.

The operation of the invention has been described to some extent in connection with the construction thereof. Since the chair is shown in the drawings in its set-up arrangement, let it be assumed that the chair is thus set up and is folded into a compact bundle. To accomplish this, the leg rest unit 11 is detached from the chair unit 10 by unhooking the hooks 63 from the apertures 62 in the cross bar 38. Pressure is applied to the straps 74 and 75 or 92 and 93 in the region of their hinge pin portions 81 or 98, as by placing the knee thereat, as a fulcrum, at the same time pulling the ends toward one another, thereby folding the spreader 73 or 91 so that the straps 74 and 75 or 92 and 93 lie alongside one another. While this is occurring, the longitudinal frame members 64 are pushed toward one another until they lie alongside each other. The leg members 68 and 69 are swung toward one another, pivoting around the fastener 70 (Figure 3) until their end pins 67 come out of the sockets 66, whereupon they, too, slide alongside one another like the halves of a pair of scissors. Meanwhile, the flexible cross members 87 and 28 have collapsed, causing the slats 88 to lie alongside the longitudinal frame members 64. All parts of the leg rest unit 11 may thus be collapsed and strapped together into a single elongated bundle.

The chair unit 10 is collapsed by first unhooking the flexible connectors 51 from the hooks 52, after which the cross bars 26 and 38 are pulled out of their wedge and socket connection with the uprights 12 and standards 42 respectively. The spreader 14 is then collapsed by pulling the parts 16 and 17 thereof upward around the pivot pin 18, thereby enabling the standards 42 and uprights 12 to be folded into an elongated bundle alongside one another. The arm rests 54 are removed merely by lifting their outer ends upward and sliding them off the ends of the uprights 12. The flexible chair back 36 may be rolled up around one of the cross bars 26 or 38 or merely folded up. Optionally, the various parts of the leg rest unit 11 and chair unit 10, excepting the chair back 36 and cross bars 26 and 38, may be laid out on the floor, ground or deck, alongside one another and rolled up in the chair back 36, with the cross bars 26 and 38 inside and outside the bundle respectively. The entire assembly may then be stowed away in a small space, such as in a vehicle.

To set up the chair, the foregoing operations are reversed in an obvious manner.

While I have shown and described my invention in detail, it is to be understood that the same is to be limited only by the appended claims, for many changes may be made without departing from the spirit and scope of my invention.

What I claim is:

1. An adjustable arm rest for a chair having

inclined uprights, comprising an elongated plate-like member having near one end thereof an elongated aperture for the passage of said inclined upright, said aperture having a length exceeding the length of a horizontal section through said upright at the point of attachment of said member, the inner end of said aperture having a doubly inclined portion of V-shaped cross-section with two relatively-angled faces, one of which faces is adapted to engage the inclined edge of either upright, one of said angled faces being directed upward to engage said inclined upright as a limiting stop upon adjusting said arm rest and the other angled face being directed downward to abut to said inclined upright in the working position of said arm rest.

2. An adjustable arm rest for a chair having inclined uprights, comprising an elongated plate-like member having near one end thereof an elongated aperture therein arranged obliquely thereto in a lengthwise direction for the passage of said inclined upright whereby to position said arm rests out of parallelism with one another, said aperture having a length exceeding the length of a horizontal section through said upright at the point of attachment of said member, the inner end of said aperture having a doubly beveled portion of V-shaped cross-section with two relatively-angled faces, one of which faces is inclined at substantially the same angle to the horizontal as the inclined edge of said upright, one of said angled faces being directed upward to engage said inclined upright as a limiting stop upon adjusting said arm rest and the other angled face being directed downward to abut said inclined upright in the working position of said arm rest.

3. An adjustable arm rest for a chair having inclined uprights, comprising an elongated plate-like member having near one end thereof an elongated aperture therein arranged obliquely thereto in a lengthwise direction for the passage of said inclined upright and effecting divergence of the opposite arm rests relatively to one another, said aperture being of substantially the same width as said upright but having a length exceeding the cross-sectional dimension of said upright.

CHAS. E. MEEKER.
